INVENTOR

ATTORNEY

UNITED STATES PATENT OFFICE.

JOHN H. BEATTY, OF CANTON, OHIO.

SURGICAL DEVICE.

1,245,858.

Specification of Letters Patent.

Patented Nov. 6, 1917.

Application filed August 20, 1917. Serial No. 187,045.

To all whom it may concern:

Be it known that I, JOHN H. BEATTY, a citizen of the United States, residing at Canton, in the county of Stark and State of Ohio, have invented a new and useful Surgical Device, of which the following is a specification.

My invention relates to improvements in surgical devices, more especially designed 10 for finger splints or cots and has for its object means whereby the splint or cot can be adjusted so as to arrange the tangs or members of the splint or cot in such a way that they can be adjusted to provide for different 15 injuries both as to kind and also location.

It will be understood that my invention may be embodied in a variety of mechanical forms, the most desirable being illustrated in the accompanying drawings.

20 In the accompanying drawing:

Figure 1 is a plan view showing the members properly attached.

Fig. 2 is a section on line 2—2, Fig. 1.

Fig. 3 is a view showing the members 25 bent or folded to produce a cot.

Fig. 4 is a plan view showing a slight modification.

Fig. 5 is a section on line 5—5, Fig. 4.

Similar numerals of reference indicate 30 corresponding parts throughout the several figures of the drawing.

In the accompanying drawings, the numerals 1 and 2 represent the splint or cot members, which are formed of the proper 35 lengths to produce a finger cot or splint, when the same are folded or brought into the position illustrated in Fig. 3. The members 1 and 2 are formed of thin, bendable material preferably of metal, but not necessarily so. One of the members, as shown 40 in the drawings the member 1, is provided with the strip 3, which is formed of a length to correspond substantially with the width of the member 2, by which arrangement the member 2 is located between the strip 3 and the face of the member 1, by which arrangement the member 1 can be moved laterally upon the member 2 or the member 2 can be moved endwise upon the member 1. In the

drawings I have shown the member 1 moved 50 laterally. It will be understood that by adjustably attaching the cross members 1 and 2 any desired adjustment as to length of the splint members can be made, which is of importance, not only in providing for the 55 proper bandaging of injuries or sores, but also provides means whereby a splint member may be sufficiently lengthened to facilitate the proper bandaging in various ways.

Referring to the construction illustrated 60 in Figs. 1 to 3 of the drawings it will be noted that the detachable connection between the members 1 and 2 is obtained by providing two parallel longitudinally disposed slits in the member 1 at a point intermediate the extremities thereof, said slits being in length substantially the width of the member 2; and the metal between the slits is depressed for a distance approximately the thickness of the member 2, thus 65 forming a depressed strip of the proper proportions to receive the member 2 and allow for longitudinal adjustment and detachment of said member 2.

In Fig. 4 I have illustrated a slight modification which consists in forming tangs 4, which take the place of the strip 3 but it will be understood that the adjustable feature is maintained in both instances.

It will be understood that the members 80 1 and 2 are capable of being detached, one from the other by means of which the members can be laid side by side or placed in bundles for shipping or storing purposes.

Having fully described my invention what 85 I claim as new and desire to secure by Letters Patent, is:

1. A surgical splint of the character described consisting of a pair of pliable strips adjustably connected together between their 90 ends and extending at substantially right angles to each other, said strips being bent in approximately parallel relationship to form a cot for engagement over or upon a finger.

2. A surgical splint of the character described, comprising a pair of pliable members, one of said members provided inter-

mediate its extremities with a depressed strip through which the other member is slidably located.

3. A surgical splint of the character described consisting of thin pliable strips detachably connected one to the other between their ends and extending substantially at

right angles to each other, said strips being bent in approximately parallel relationship to form a cot over and upon a finger. 10

In testimony that I claim the above, I have hereunto subscribed my name.

JOHN H. BEATTY.
